UNITED STATES PATENT OFFICE.

GEORGE W. MAXWELL, OF SAN FRANCISCO, CALIFORNIA.

RECEPTACLE-FORMING MACHINE.

No. 872,835.

Specification of Letters Patent.

Patented Dec. 3, 1907.

Application filed January 2, 1906. Serial No. 294,218.

To all whom it may concern:

Be it known that I, GEORGE W. MAXWELL, citizen of the United States, residing at San Francisco, in the county of San Francisco and State of California, have invented certain new and useful Improvements in Receptacle-Forming Machines, of which the following is a specification.

My invention relates to receptacle forming machines, and more particularly to machines for forming containing vessels from fibrous material for dispensing different articles, preferably milk.

The object of the invention is to produce a machine in which blanks of material, preferably sheets of thick paper or card board, are automatically fed in succession to gluing and beveling mechanism, then passed to formers and folded into hollow bodies, then securing a bottom in each body, and finally ejecting the completed article.

An embodiment of the invention is shown in the accompanying drawings in which:

Figure 1 is a broken side elevation, some of the parts being omitted to avoid confusion. Fig. 2 is a similar front elevation, Fig. 3 is a similar plan view, Fig. 4 is a sectional view on line 4—4 of Fig. 3 looking in the direction of the arrow, Fig. 5 is an inverted plan view of the ejector mechanism, Fig. 6 is an enlarged detail view of the folding mechanism, Fig. 7 is a transverse sectional view of the trimming and gluing mechanism; Fig. 8 is a sectional view of the bottoming mechanism on the line 8—8 of Fig. 2, Fig. 9 is a detail view of the same, Fig. 10 is a detail view of the means for actuating the lower folder. Fig. 11 is a detail perspective of the connections for operating the bottom-seating mechanism.

Referring more particularly to the drawings, 1 indicates the frame, across the rear portion of which is mounted the main shaft 2, which is driven from any source of power, 45 not shown, preferably by a sprocket wheel 3 and chain 4. Located substantially in the center of the frame is the magazine 5, in which are placed the blanks 6 from which the articles or containers are to be formed. 50 The blanks are fed from the bottom of the magazine, one at a time, by a reciprocating feeder 7, which is preferably secured to or mounted on a slide 8, which is adapted to be moved back and forth on a bar 9, by a lever 55 10 and link 11.

The lever is swung on its pivot by a link 12 which is connected with a crank or wrist pin 13 on a mutilated gear pinion 14. The pinion is adapted to be intermittently driven by a gear wheel 15 on the main shaft 60 2. The teeth of the pinion are thrown into mesh with the gear 15 at the proper time by projections 17 on the pinion which are engaged by pins 18 on the gear and thereby given a slight movement forward. The 65 feeder is provided with yielding blocks or fingers 19, which project above the bottom pieces 20 of the magazine just the thickness of one blank, so that when it is carried forward by the above described mechanism the 70 fingers will carry the blank forward under the lower ends of the front bars 21 of the magazine and deposit it upon a carrier 22. On the return movement of the feeder the fingers are caused to bend forward and slide 75 under the pile of blanks without disturbing them and the feeder is moved far enough to the rear to permit of the fingers assuming their normal position before being carried forward to engage with another blank.

The carrier is mounted on the upper end of an arm 23, which is swung back and forth by a lever 24 and link 25. The carrier is moved forward to deposit the blank by a pin 26 on the wheel 15 which engages with the 85 lever 24, and it is returned for another blank by a spring 27 which is preferably connected with the arm 23. The carrier is held in its normal position by the lever 24 resting on the shaft 2.

The blank is deposited by the carrier upon a platform 28 where it is rigidly held by a clamp 29, which is reciprocated, or moved toward and from the platform by a stem 29' and gear segment 30 which engages with a 95 rack 30' on the stem. The rack is guided in its reciprocation by a guide pin 31 and the segment is mounted on a rock shaft 32, which is oscillated by a lever 33 and link 34. The lever is actuated by a crank or wrist pin 35 mounted on a pinion 36 and working in a slot 37 in the free end of the lever. The pinion is driven by a gear wheel 38 on the shaft 2 and is mutilated so as to only move the clamp at suitable intervals to correspond with the 105 operation of the other mechanism. Pins 39 on the wheel 38 throw the teeth of the pinion into mesh at the proper times by engaging with projections 40 on the pinion.

After the blank has been deposited upon 110

the platform and while it is held by the clamp, one of its edges is chamfered or beveled off so that when the blank is rolled into tubular form and its edges overlapped, the 5 bevel will cause the surface of the tube to be smooth or even. In the drawings I have shown only one edge beveled to form a smooth interior but it is evident that both edges could be beveled by simply duplicating 10 the beveling mechanism, but which I have thought it not necessary to show. In the form of mechanism which I have shown and prefer for beveling the edge of the blank, a block or slide 41 is mounted in a guide way 15 42 arranged parallel with the edge to be beveled and the block is moved back and forth by a lever 43 and link 44. A cutter 45 is mounted on the slide in position for engaging with the edge of the blank and is driven by a belt 46 from any suitable source of power, not shown. The lever 43 is moved forward by a lever 47 and link 48 at the desired rate of speed to do the cutting, and the lever 43 is actuated by a pin 49 on the gear wheel 38. 20 25 A spring 50 connected with the lever 47 returns the cutting mechanism after the edge has been beveled.

At the same time that one edge or end of the blank is being beveled the other end receives 30 a line of adhesive material from a tank 51, as by means of a bar 52, which is pivotally supported on a rock shaft 53, the bar being normally submerged in the contents of the tank, which is preferably glue. The 35 shaft 53 is rocked at the proper time to glue the blank by a lever 54 and link 55, the lever being actuated by a cam 56 on the shaft 2, and held in engagement therewith by a spring 57.

40 After the blank has been beveled and glued it is fed forward onto the forming mechanism by a reciprocatory clamp 58 which is connected with the upper end of the lever 10. The upper jaw 59 of the clamp is 45 spring pressed and adapted to be opened by a shoulder or projection 16 on the lever 10 which engages with a pin 60 on the jaw and lifts it up when the lever is swung back in returning the feeder 7 for another blank. As 50 the clamp is moved forward the jaw is permitted to gradually close so that by the time the clamp has been moved forward to secure a good hold upon the rear edge of the blank the jaw is completely closed and the blank is 55 carried forward thereby until it lies directly above a block or former 61, which is preferably cylindrical and tapering, as the frustum of a cone.

When the blank is deposited upon the 60 platform 28, it is preferably positioned by reciprocatory pins 62 at the front and one end and inclined pins or guides 63 at the rear and the other end. Before it is moved forward to the formers the pins 62 are depressed, as by gear pinions 64 and racks 65,

which pinions are actuated by a rock shaft 66. The shaft is provided with two arms 67 and 68, set at such an angle to each other that the movement of one of them to rock the shaft sets the other in position to be engaged and thereby return the shaft to its former position. The arm 67 for depressing the pins is located in the path of a push rod 67' which has one end connected with the lever 47 and its other end with a link 68'. The 70 arm 68 for elevating the pins is in the path of a projection 69 on the lever 10 which causes the pins to rise just in time to receive a blank from the carrier 22.

The formers 61 are preferably secured 80 radially to the periphery of a wheel 70 by means of standards or vertical brackets 71. The wheel is mounted on a spindle 72 at the outer ends of inclined arms forming a part 85 of the main frame and projecting from the front thereof and is rotated, step by step, by a pawl 73 on a reciprocatory bar 74 so as to successively bring the formers under the blanks as above described. The bar 74 is drawn forward to rotate the wheel by a rack 90 at one end thereof and a segmental gear 75 which gear is driven from the main shaft 2 by a shaft 76 and bevel gearing 77, and the bar is returned by a spring 78. The teeth of the segment are caused to register with those of the rack by one end of the segment engaging with a projection 79 on the rack and giving the rack a slight movement before the teeth are thrown into engagement. After the segment passes out of engagement with the rack a pin at the rear end of the segment engages with an inclined projection on the rack and acts as a brake to prevent the spring 78 from drawing back the bar too rapidly. 95

105 The wheel 70 is locked with a former in position to receive a blank by a shoulder 80, against which a projection 81 at the upper end of each bracket 71 is adapted to engage as the wheel is moved forward by the pawl 110 73. The pawl is pivotally secured so as to pass under the lower end of the bracket 71 on the return movement of the bar 74, and it is preferably yielding, as by mounting it at the upper end of a pivoted arm 82, the lower end 115 of the arm being connected to a spring 83. The stop or shoulder 80 is also preferably yielding, as by utilizing or forming it at the lower end of a pivoted arm 84, the upper end of the arm being connected with a spring 85. The shoulder is formed on or connected with a laterally movable bar 86, which is pivotally secured at one side of the machine and supported in a stirrup 87 at the other side, and provided with a deflector 88 at a distance 120 from the shoulder 80 equal to the width of the projection 81. One side or face of the deflector is slightly inclined so that when it is engaged by the projection 81, the bar 86, which is normally held in its locking 125 position, is moved laterally to a position 130

position by a spring 89, will be drawn over until the projection has cleared the deflector, when the spring will immediately draw the bar back and cause the projection to stand 5 between the deflector and the shoulder 80.

Before moving the wheel forward after a blank has been deposited on the former, the free end of the bar 86 is moved laterally in the stirrup by a lever 90, which moves the shoulder 80 from in front of the projection 81 and permits the pawl 73 to move the wheel forward another step. The lever 90 is actuated by a cam 91 on the shaft 76 which engages with an inclined surface 92 on the lever 6 and throws the bar over after which the spring 89 will return the bar to its normal position as soon as the cam passes out of engagement with the incline 92.

When the wheel is standing in its locked position the forward end of one of the formers 61 is held adjacent to the end of bar 9, with a pin 93 in its end resting on support 94 on the frame 1, so that as the clamp 58 moves forward the blank slides upon the former until its forward edge engages a stop 95 on the former and the clamp enters a slot 96 formed longitudinally in the end of the former. The stop 95 is preferably made adjustable, as by slotting it and fastening it in position, as with an ordinary screw. This secures accuracy in forming the receptacle when it is intended to hold a predetermined quantity, as milk, for which the receptacle is particularly adapted. In case the edge of the blank should engage with the stop before the clamp 58 reaches the forward limit of its movement the spring pressure upon the jaw 59 will permit of the clamp moving forward a short distance without moving or damaging the blank.

After the blank has been deposited on the former in this manner, a pair of reciprocating press-like clamps or folders 97 descend and, owing to their being substantially inverted U-shape, they press the blank down upon the upper portion of the formers with the ends of the blank projecting below it substantially parallel. After that the ends are folded in upon the under side of the former with their edges overlapping, by two side folders 98 and 99 and a bottom folder 100. The top and side folders are operated by a train of gear wheels 101, 102 and 103, of substantially the same size, and three mutilated pinions, 104, 105 and 106, which mesh respectively therewith. The wheels are driven from a gear wheel 107 on shaft 76 through a pinion 108, and sprocket wheels and a chain 109, and the pinions are thrown into engagement with their respective wheels by pins 110 thereon and projections 111 on the pinions.

The middle wheel 102, and its pinion 105 move the top clamp or presses 97, by means of a pitman 112 which is connected with a

stem 113 projecting upward from the head 114, and thereby causes the head to be reciprocated on downwardly extending pins 115. The arms or levers 116 and 117 which carry the side clamps, respectively, are pivotally mounted on the stem 113, and the clamps, which are curved and rigidly secured to the free ends of the levers, are carried respectively above and below the plane of the blank by the reciprocation of the head 70 114. After the presses 97 have been lowered to seat the blank on the former, the pinion 105 stops rotating and the side clamps are moved toward the former, one in advance of the other, the folder 98, which folds the beveled edges, moving slightly ahead of the folder 99, and after reaching the limit of its movement the pinion 106, which controls it, is disengaged from its gear wheel 103, and like the pinion 105, remains stationary until 75 80 the folding process is completed. When the parts stand in this position the beveled edge abuts or rests against the opposite or glued end of the blank at substantially a right angle and the further inward movement of 90 the folder 99 would have a tendency to bend or crumple the thin beveled edge in trying to force it in against the former. To prevent this the pinion 104 is stopped and the bottom folder 100 is moved up into engagement with 95 the projecting or glued end of the blank which causes it to bend and present an inclined surface upon which the beveled edge will slide. The pinion 104 is then again thrown into engagement which will cause the 100 folder 99 to force the glued or overlapping end inward simultaneously with the continued upward movement of the bottom folder 100 until the lap is completed when the pinion 104 again stops and the bottom 105 folder completes its movement and holds the overlapping ends of the blank together. After the blank is thus secured all of the pinions are thrown into engagement with their respective gear wheels and the top and side 110 folders are returned to their normal position, when they again stop and remain stationary until another blank has been deposited and the folders are again operated as above described.

The bottom folder 100 is pivotally mounted in its support and provided with a tail piece or projection 118, which is adapted to be engaged by the free end of a push bar 119 that is mounted on two legs or supports 120 120 and 121. The leg 120 is pivoted at such a distance in advance of its connection with the bar that, as the bar moves forward from its normal position, its free end will engage with the projection 118 and follow it up as 125 the folder is swung upon its pivot until a pin 122 on the projection engages with a latch 123 and locks the folder in engagement with the lap of the blank on the former as above described. The free end of the other leg 121 130

extends above its connection with the bar and is adapted to be engaged by a pin 124 on the wheel 107.

Located directly below the folder 100 is a 5 gas jet or burner 125, which is supplied from a reservoir 126 at the center of the wheel 70 through a pipe or tube 127, the reservoir being supplied from any suitable source of supply, not shown.

10 After the blank has been folded around the former and clamped by the heated folder 100, the wheel 70 is unlocked and fed forward, step by step, as hereinbefore described, until the former carrying a blank 15 has almost made a complete cycle and reaches the ejector mechanism, just before which the latch 123 is moved into engagement with a stop 128, which causes it to release the bottom folder and permit the folder 20 to fall away from the former. By this time the glue has become thoroughly dried and the blank has been formed into an open ended tapering conical tube ready to have a bottom inserted therein.

25 Mounted radially of the wheel 70 and directly above the former from which the bottom folder has just been released, is a reciprocatory plunger 129 to which are secured two depending brackets 130. The plunger 30 is moved forward and back by a gear wheel 131 and rack 132, and to the lower end of each of the brackets is pivotally secured a forwardly extending, spring pressed arm 133. A curved head or ejector 134 is secured to 35 the free end of each arm which is adapted to be forced into engagement with the former by a pin 135 which is adapted to engage with a guide 136. There are two guides which have their forward ends free and inclined toward each other, whereby, when the plunger is moved forward the heads will be forced in against opposite sides of the former to the rear of the larger end of the tube and held in yielding engagement therewith until 45 they have forced the tube off the tip or smaller end of the former. By the time this has been done, another blank has been deposited upon the former which has been locked below the folding mechanism, and the 50 wheel is then again unlocked and fed forward another step which places another former in position to receive a blank and another former in position to have a tube removed therefrom. The wheel 131 is oscillated to reciprocate the plunger by a toothed bar 137 which is actuated by a cam 138 on the main shaft 2 and a lever 139, the wheel being wide enough to have the bar and rack both engaging therewith at the same time, 55 one above the other.

When the tube passes off the end of the former it drops into a basket or cage 140 depending from one end of the plunger support 141, which overhangs a horizontally arranged rod or carrier 142, in which are

formed openings or pockets 143. The rear end of the cage 140 is in the form of a loop which engages with the larger end of tube as it falls from the former, while the forward end is formed from slender arms, two of 70 which are at the sides and the other one at the end of the tube, which will cause the smaller end of the tube to fall down into one of the pockets 143, while the loop at the rear, by arresting the downward movement of the 75 larger end of the tube, will cause the tube to assume a substantially vertical position in the pocket, something like a hopper.

The reel is caused to revolve, step by step, by a spring pressed pawl 144, which is pivotally mounted on the end of the reciprocatory bar 74 which is extended under the reel in position to let the pawl engage with shoulders thereon, as the spokes of the reel. In its revolution, the reel carries the tube under 80 a magazine 145 in which are stored the bottoms therefor and from which the bottoms are discharged, one at a time, into the tubes by an ejector 146. The ejector is reciprocated by two levers 147 and 148 which are connected by a link 149, and actuated by a cam 150 on a shaft 151, which in turn is driven from the shaft 2 by gear wheels 152. The ejector is yieldingly forced forward by a spring 153 which engages with the lever 148, 85 while it is drawn back positively for engaging with another bottom by the engagement of the cam 150 with said lever 148. In this manner the liability of damage to the machinery by the failure of the ejector to discharge a bottom is avoided.

Just before the bottom is deposited in the tube, a temporary support, as a circular platform 154, is permitted to rise in the lower end of the tube and cause the bottom to rest at 105 right angles to the axis of the tube and thereby prevent its being caught or held in the wrong position. After the bottom has been deposited in this manner, a plunger 155 descends and forces it down into the tapering 110 end of the tube until its edges engage so firmly therewith that a water tight joint is formed and the bottom will be held against accidental displacement. The plunger is reciprocated by a lever 156, which is connected 115 by a link 157 with the plunger rod below a head 158 and the lever is depressed by a cam 159 on the shaft 151, and returned to its normal position by a spring 160.

As it is desirable for the bottom to be 120 finally seated with a slow movement, and owing to the speed with which the plunger must travel to enter the long tube and be withdrawn in time to permit of the rotation of the reel, a supplemental lever 162 is arranged to engage with the head 158 with its short end when the plunger is depressed, while its long end is actuated by a cam arm 163 on the shaft 151. As the lever 162 normally stands with its short end retracted or 125

withdrawn, it is necessary to throw the head under said end after it descends far enough to be engaged thereby, which is done by inclining one edge as at 164 which, engages 5 with a pin or upright 165, and causes the head to be swung in under said end of the lever and be engaged thereby when the free end of the lever is engaged by the cam arm 163.

10 During the final pressure upon the bottom the tube is supported by its lower edge resting upon a movable platform 166, which is swung up into position by a lever 167 that engages at one end with the platform and 15 has its opposite end in position to be depressed by a pin 168 on the link 157, which causes the platform to rise simultaneously with the depression of the plunger. The platform is slotted for the passage of the 20 stem of the circular platform 154 and the circular platform is reciprocated or withdrawn from the bottom of the tube by a push rod 169, to permit the reel to rotate and the rod is connected with the stem of the platform 25 by a bell crank lever 170. The rod is held in its retracted position by a spring 171 and is moved forward to depress the platform by a cam 172 on the shaft 157.

After the bottom has been placed in position as above described the receptacle is carried forward by the reel until it is engaged by an upward extension or finger 173 on the forward end of a lever 174, which engages with the bottom and lifts the receptacle up out of 35 its pocket, whence it may be moved in any desired manner but preferably carried by suitable mechanism, not shown, through a paraffining bath, as shown in dotted lines at 175. The lever 174 is actuated by a cam 40 arm 176 on the shaft 151, and the arm also actuates a lever 177 which is shouldered at its forward end so as to engage with a shoulder on the reel, as one of its spokes, and stop the reel with its pockets in position for one 45 receptacle to be ejected while the bottom is being placed in another and a completed tube is deposited in another.

In operating a machine as above described, the magazine is supplied with blanks 50 and power applied which causes the bottom blank to be carried forward and deposited upon the platform where one end is beveled and the other end glued. The blank is then fed forward and deposited upon one of the 55 formers which is locked in position for receiving it, after which it is folded around the former and held thereon until the glue has become dried and it is carried around to the ejector mechanism. From there it is 60 charged into the bottoming mechanism where the bottom is put in and the receptacle is discharged, complete and ready for use for many purposes, or for further treatment to prepare it for use for other purposes, as de-

sired. As the machine is adapted to be 65 operated step by step and can be provided with a large number of formers, the different steps in the process of manufacture can be carried on simultaneously upon different receptacles, where the capacity of the machine will be very large. 70

Although I have shown a form of mechanism which I have found very efficient for practicing my invention, it is evident that modifications can be made therein, and I reserve the right to make all such changes and alterations therein as will come within the scope of my invention. For instance, the edge of both ends of the blank may be beveled as hereinbefore mentioned, which 80 adapts the receptacle for receiving a cap-like bottom upon its exterior, and angular receptacles can be formed instead of cylindrical by constructing the former with the desired outline or cross section and making the fold- 85 ers of the proper shape to conform thereto. Or electricity can be used for drying the glue instead of gas.

Having described my invention, what I claim as new and desire to secure by Letters 90 Patent, is—

1. In a receptacle forming machine, means for successively feeding blanks of fibrous material thereto, means for beveling the edge of one end of the blank, means for forming the 95 blank into a tubular body with the beveled edge upon the interior, and means for inserting a circular bottom within said body.

2. In a receptacle forming machine, a clamp, means for feeding blanks thereto, 100 means for beveling the edge of one end of the blank and placing a line of adhesive material upon the other end while the blank is within said clamp, and means for forming each blank into a body having a circular cross 105 section with the adhesive end overlapping the beveled end.

3. In a receptacle forming machine, a clamp, means for feeding blanks thereto, 110 means for beveling one end of each blank while it is in the clamp and gluing the other, a plurality of formers, a reciprocatory clamp for moving each blank from the first mentioned clamp to one of said formers, means for stopping the blank before the reciprocating blank reaches the limit of its movement, and means for folding the blanks around the former with the glued end overlapping the beveled end. 115

4. In a receptacle forming machine, a 120 clamp, guide pins thereon, part of which are vertically movable and the others all inclined, means for successively feeding blanks of fibrous material to said clamp, means for beveling the edge of one end of the blank 125 and gluing the other, a plurality of formers, means for depressing the movable pins, means for moving each blank onto a former

while said pins are depressed, and means for folding each blank around its former with the glued end overlapping the beveled end.

5. In a receptacle forming machine, a magazine for blanks of fibrous material, a platform provided with guide pins, part of which are movable, a feeder under the magazine provided with yielding fingers, a carrier between the feeder and the platform, means for beveling the edge of one end of the blank and gluing the other end while the blank is held on said platform, a plurality of formers, means for depressing the movable pins, means for moving the blank from the platform to one of the formers while said pins are depressed, and means for folding each blank around its former with the glued end overlapping the beveled end.

6. In a receptacle forming machine, a magazine for blanks of material, a platform, a bar under the magazine and the platform, a feeder reciprocally mounted on the bar provided with yielding fingers, a carrier between the feeder and the platform, a plurality of formers, each adapted to be alined with said bar, a reciprocating clamp on the bar for moving the blank from the platform to the former, and means for forming the blank into a hollow body while on the former.

30 7. In a receptacle forming machine, a plurality of slotted formers, each provided with a stop, and a reciprocatory clamp adapted to enter said slots and move a blank into engagement with said stop and permit the clamp to move upon the paper after the paper has engaged with said stop.

8. In a receptacle forming machine, a platform, vertically movable pins therein, a rock shaft provided with arms and means for moving the pins, means for passing blanks over the platform, means for engaging with one of said arms to rock the shaft and move the pins and the other arm in one direction, and means for engaging with said other arm to rock the shaft and move the pins and the first mentioned arms into their original position.

9. In a receptacle forming machine, a platform, a vertically movable clamping member, a rock shaft for actuating said member vertically, movable pins in the platform, a rock shaft for moving the pins, a reciprocally mounted cutter at one end of the platform, two levers, one of which is adapted to rock the first mentioned shaft and control the clamp and the other is connected with the cutter and provided with means for rocking the other shaft, and means for intermittently operating said levers.

60 10. In a receptacle forming machine, a plurality of formers, each provided with an adjustable stop, a yielding clamp for feeding blanks against said stops, and means for folding the blanks around the formers.

65 11. In a receptacle forming machine, a

plurality of formers, a slotted stop on each former, a clamp provided with a spring pressed jaw for feeding blanks against said stop, and means for folding the blanks around the formers.

70 12. In a receptacle forming machine, a former, a plurality of folders therefor, two at the sides and one at the top and bottom respectively, means for operating one of the side folders intermittently, and means for 75 imparting a relatively continuous movement to the bottom folder.

13. In a receptacle forming machine, a former, a reciprocally mounted stem provided with clamp like folders, oppositely 80 extending levers pivotally mounted on the stem, the free end of each lever being provided with a curved folder, means for moving one of the levers and its folder intermittently, a folder at the bottom, and means for 85 actuating said bottom folder continuously during the intermittent action of the side folder.

14. In a receptacle forming machine, a former, a reciprocally mounted top folder 90 and two pivotally mounted side folders, a train of gear wheels, each provided with pins, mutilated pinions for controlling the folders, one for each wheel, and each pinion provided with projections for being engaged by said pins, and a bottom folder.

15. In a receptacle forming machine, a rotary member, a plurality of formers radially mounted thereon, means for rotating said member intermittently, means for folding a 100 glued blank around each former at one point and ejecting it at another, and means for drying the glue intermediate said points.

16. In a receptacle forming machine, a wheel, formers radially secured to the periphery thereof, means for rotating the wheel intermittently, means for folding a glued blank around each former at one point with its ends overlapping, and ejecting it at another, said folding means including a heated 105 member which engages with said fold and dries the glue, and means for releasing said heated member before it reaches the ejector.

17. In a receptacle forming machine, a plurality of formers, means for folding a 110 blank of glued material on each former with its ends overlapping, said means including a pivoted member, a latch for holding said member in engagement with the overlapped portion, means for heating said member, 115 means for automatically releasing said member, and means for ejecting the folded material.

18. In a receptacle forming machine, a wheel, brackets secured to the periphery thereof, the upper end of each bracket being provided with a projection, radially arranged formers secured to the upper ends of said brackets, a bar provided with a stop and a deflector for engaging with said pro- 120

130

jections and locking the wheel against rotation, means for moving said bar to unlock the wheel, and a reciprocatory bar provided with a yielding pawl for engaging with the lower ends of said brackets and rotating the wheel.

19. In a receptacle forming machine, a wheel provided with brackets radially arranged formers secured to the brackets, a spring actuated reciprocatory bar provided with means for intermittently rotating the wheel, a rack and a stop at one end of the bar, and a toothed quadrant, one end of which is adapted to engage with said stop and move the bar to cause its teeth to be engaged by the teeth of the quadrant.

20. In a receptacle forming machine, a frame provided with blank preparing mechanism, means on one side for forming the blanks into hollow bodies, means on another side for putting bottoms in the bodies, and means for discharging the bodies from the formers to the bottoming mechanism.

21. In a receptacle forming machine, a wheel provided with radially arranged formers, a radially arranged reciprocatory bar provided with downwardly extending brackets, an arm pivotally secured to each bracket, the free end of each arm being provided with a curved head, a pin in each head, and yielding guides for engaging with said pins.

22. In a receptacle forming machine, a wheel provided with radially arranged formers, means for rotating the wheel intermit-

tently, a radially arranged reciprocatory bar provided with a rack at one end and ejectors at the other, a wheel engaging therewith, a reciprocatory bar engaging with said wheel at an angle to the first mentioned bar, and means connected with the wheel operating mechanism for actuating the second mentioned bar when the wheel is at rest.

23. In a receptacle forming machine, a series of radially arranged formers, a rotary reel provided with pockets, a cage above said reel, the forward end of which is open at the bottom and the rear end is closed, and means for ejecting hollow bodies from the formers through the basket into said pockets.

24. In a receptacle forming machine, a wheel provided with formers, means for forming a hollow body on each former, a rotary reel provided with pockets, a reciprocatory bar provided with two pawls one of which engages with the wheel and the other with the reel, means for removing said bodies from the formers to said pockets, and means for inserting a bottom in each body.

In testimony whereof I have affixed my signature, in presence of two witnesses, this 22d day of December, 1905.

GEORGE W. MAXWELL.

Witnesses:

M. R. SEELY,
F. M. BARTEL.
